APPARATUS FOR PRESHRINKING
TEXTILE FABRICS

Georg Schlenk, Berlin-Spandau, Germany

Application August 18, 1939, Serial No. 290,816
In Germany August 18, 1938

10 Claims. (Cl. 26—18.6)

This invention relates to an apparatus for preshrinking textile fabrics in continuous webs by mechanically pushing the threads of the fabric closer together. Such apparatus serve for imparting to the fabric a preshrinkage which compensates for the shrinkage in washing, so that the garment made of the fabric cannot shrink further in the wash. The densification of fabrics for other purposes can also be attained by this means.

The invention relates to an advantageous construction of such a device which is relatively simple and cheap. By the apparatus according to the invention an effective densification of the fabric is obtained when the shrinking is carried out. Moreover, by this means a high degree of densification of the fabric is attained so that a relatively wide range of densification is obtainable and a densification is possible for all instances occurring in practice. At the same time the degree of densification can be regulated in a simple manner within the said range of densification by the apparatus according to the invention.

25 Three embodiments of the invention are illustrated by way of example in the accompanying drawing, in which:

Fig. 1 shows the apparatus in top plan view,
Fig. 2 is a section on line 2—2 of Fig. 1,
30 Fig. 3 shows a modified form of construction in top plan view,
Fig. 4 is a side elevation of Fig. 3,
Fig. 5 shows in side elevation and on a larger scale a portion of the construction illustrated
35 in Fig. 3,

Fig. 6 shows a third form of construction in top plan view.

In the drawing the same references are used for the same parts in the different figures. The form of construction illustrated in Figs. 1 and 2 comprises a support in the form of a rectangular plate 1 which is preferably slightly bulged and over which the web 2 of the fabric to be densified is guided. This web is fed over a roller 3 to the left end of the support plate 1 and runs off the right end of the plate over a roller 4. The web 2 therefore moves over the plate 1 in the direction of the arrow shown in Fig. 2, which also indicates the direction in which the densification of the fabric takes place and which is herein-after referred to as the pushing together direction.

An elastic band 5, for example of rubber, is arranged above the fabric web 2. On this band means act which impart to it a reciprocating

swinging or oscillating movement over the fabric web 2, the length of the band being varied at the same time. These means in the form of construction illustrated in Figs. 1 and 2, consists of two cranked shafts 6 and 7 rotating at the same speed and to whose middle parts 8 and 9 the end of the elastic band 5 are secured. On each of these middle parts a metal sleeve 10 or 11 is mounted so that it is freely rotatable thereon. Around these sleeves 10, 11 the ends of the band secured thereto are wrapped. The lateral arms of the two cranked shafts 6 and 7 are in corresponding parallel positions which they retain continually during their rotation at the same speed. For this purpose the cranked shaft 7 on the right is driven by the cranked shaft 6 on the left through the intermediary of a bevel wheel gear 12, 13 and 14. The lateral arms 15 and 16 of the cranked shaft 6 on the left are longer than the lateral arms 17 and 18 of the cranked shaft 7 on the right so that, as can be seen from Fig. 2, the middle part 8 of the left shaft 6 describes a circle with larger radius 19 than the middle part 9 of the right shaft 7 whose circle has the smaller radius 20.

To enable the amplitude of oscillation of the elastic band 5 to be adjusted as desired, the length of the lateral arms 15 and 16 of the left cranked shaft 6 determined by the distance of the middle part 8 from the axis of rotation *a—b*, is 30 adjustable. For this purpose these arms engage in sleeves 21 and 22 from which they can be pulled out more or less or into which they can be pushed any desired distance, as the desired amplitude of oscillation of the elastic band 5 35 may require. The arms 15 and 16 are held in the sleeves 21 and 22 by set screws 23 and 24 which can easily be loosened. The sleeves 21 and 22 carry the journals 25 and 26, the journal 26 being extended and forming the shaft of one of 40 the cone pulleys of a known cone pulley gear 27 serving for varying the speed of rotation and whose other cone pulley is mounted on a shaft 28 carrying the driving pulley 29. By changing, by means of the belt shifter fork 31, the position 45 of the belt 30 laid on the cone pulleys, the speed of the cranked shaft 6 and consequently the number of oscillations of the elastic band 5 can be changed.

The apparatus above described operates in the 50 following manner: During the rotation of the two cranked shafts 6 and 7 a reciprocating oscillating or swinging movement is imparted to the elastic band 5 over the fabric web 2, the length of the elastic band being periodically 55

changed owing to the lateral arms 15 and 16 of the cranked shaft 6 being longer than the lateral arms 17 and 18 of the cranked shaft 7. During the rotation of the cranked shafts the elastic band is also periodically raised from the fabric web 2. After having been raised from the web 2, the elastic band 5 is also stretched during its movement from the position c (Fig. 2) into the position d shown in dotted lines in Fig. 2, 10 in the direction counter to that in which the fabric is pushed together. During its return swinging movement in the direction in which the fabric is pushed together, the band contracts and at the same time acts on the fabric web 2, the elastic band 5 being then in the position e indicated in dotted lines in Fig. 2. As the under side of the band is roughened or carries projecting elements and the upper side of the support plate 1 is smooth, the fabric web 20 2 will be shifted on the plate 1 by the elastic band 5 acting on it. This band 5 thus exerts a feeding movement on to the web 2 owing to the movement imparted to the band by the two rotating cranked shafts 6 and 7, so that the web 25 2 is fed over the roller 3 to the support plate 1 and led off from this plate over the roller 4. At the same time the elastic band 5, owing to its contraction during its return swinging movement in the direction in which the fabric is 30 pushed together, also effects the densification of the fabric by pushing together in the direction of its length that portion of the web 2, which is on the support plate 1. When the elastic band 5 is in its lowered position, its two 35 ends preferably run over guide rollers 32 and 33 arranged one at each end of the support plate 1. These rollers ensure that the elastic band in its lowered position runs on to and off the support plate 1 in a uniform direction.

40 In the form of construction illustrated in top plan view in Fig. 3 and in side elevation in Fig. 4 there is also the slightly curved support plate 1 over which the fabric web 2 is fed and guided by the feed and delivery rollers 3 and 4 respectively, and the elastic band 5 located over the fabric web 2. This elastic band 5, in this form of construction, is formed by the lower side of an endless elastic band 36 guided over cylinders 34 and 35. The arrow shown in Fig. 4 indicates the direction in which the fabric web 2 is fed and at the same time the direction in which the fabric is pushed together during its densification. The cylinder 35 on the right in the direction in which the fabric is pushed together is keyed on a shaft 39 driven by a belt 37 and pulley 38. The bearings 40 and 41 of this shaft are mounted in arms 42 and 43 one on each side of the support plate 1 and are therefore stationary. On the other hand the bearings 44 and 45 of the shaft 46 of the other cylinder 34 perform a reciprocating swing motion under the action of means acting on these bearings. For this purpose the two bearings 44 and 45 form the upper ends of two vertical oscillatable levers 47 and 48 arranged one on each side of the cylinder 34, which levers are pivotally mounted at their lower end 49. The two oscillatable levers 47 and 48 are connected by a round bar 50, on which one end of a connecting rod 51 is rotatably mounted by means 55 of a sleeve 52. The other end of the connecting rod 51 is mounted on a crank pin 53 of a crank disc 54. This crank disc is rotated by the driven shaft 26 of a cone pulley gear 27 of known construction and above described, the driving shaft 28 of this gear being connected through

the intermediary of a bevel wheel gear 12, 13 and 14 to the shaft 39 driven by the pulley 38. The cone pulley gear 27 enables the speed of rotation of the crank disc 54 to be changed in known manner by shifting the belt 30 by means 5 of the belt shifter fork 31 and thus allows the changing of the number of swinging movements of the cylinder 34 reciprocated by the crank shaft, and consequently of the endless band 36 guided by this cylinder. The amplitude of oscillation of this band can be adjusted in that the crank pin 53 can be secured on the disc 54 at a variable distance from the centre thereof by means of a radial slot 55 in the crank disc, as shown in Fig. 4.

15 The endless elastic band 36 is set with bristles 56 on the entire area of its outer side acting on the fabric web 2. This is shown more clearly in Fig. 5 which is a part side elevation on a larger scale of the portion of the band laid on the left cylinder 34. The bristles 56 are inclined in such a manner that on the side 5 of the endless band 36 actually acting on the fabric web 2, the bristles point in the direction in which the fabric is pushed together. The elastic band 25 36 is preferably made entirely from rubber in which the inclined bristles 56 are embedded at one end, preferably by being vulcanized therein.

30 The form of construction illustrated in Figs. 3 and 4 operates in the following manner:

35 If the pulley 38 is driven by means of the belt 37, the endless elastic band 36 is caused to circulate on the cylinders 34 and 35 and at the same time a swinging motion is imparted to this band by the crank gear 51, 52, 53 and 54. The side 5 35 of the endless band 36 acting on the fabric web 2, owing to the circulation of the band on the cylinders 34 and 35, moves the fabric web 2 over the support plate 1, the fabric web running onto the plate over the auxiliary roller 3 and off the plate over the auxiliary roller 4. At the same 40 time the side 5 of the endless band 36, owing to the swing motion of the band, exerts a densifying action on the fabric web 2 on the support plate 1. The swinging movement of the elastic band in 45 counter-direction to that in which the fabric is pushed together and during which movement the band is stretched, takes place without exerting any influence on the fabric, owing to the bristles 56 pointing in the direction in which the fabric 50 is pushed together. However, during the return swinging movement of the band in the direction in which fabric is pushed together and during which movement the band contracts, the bristles act on the fabric and densify the same. To keep 55 the friction coefficient between the fabric web 2 and support plate 1 as low as possible the surface of the support plate is smooth. If still less friction is desired, an endless band 59 guided over rollers 3, 4, 57 and 58 may be arranged between the fabric web 2 and the support plate 1 and receive a circulating movement corresponding to the speed of the fabric web through the intermediary of driving means.

60 Fig. 6 shows in top plan view another form of 65 construction which is similar to that illustrated in Figs. 3 and 4 only with the difference that a single endless elastic band 5 of the construction shown in Figs. 3 and 4 is divided up into a plurality of separate endless elastic bands 5a, 5b, 5c 70 and 5d, and the left cylinder is divided into a plurality of rollers 34a, 34b, 34c and 34d keyed on the shaft 46 which remains unchanged. The separate endless bands are guided by these rollers at one end and at their other end run over a 75

common driving cylinder 35 which remains unchanged. This cylinder 35 is mounted in the same manner as in Fig. 3 on a shaft 39 carrying the pulley 38 driven by the belt 37. The bearings 40 and 41 of the shaft 39 are again carried in arms 42 and 43 fixed one on each side of the support plate 1. The separate endless bands are arranged at a distance apart. Additional endless bands 60a, 60b, 60c, 60d and 60e are arranged in the spaces between these bands and laterally thereof and these additional bands extend beyond the first mentioned separate bands at the left or fabric feed side and are here guided by rollers 61a, 61b, 61c, 61d and 61e carried by a common shaft 62. These additional bands also pass over the common driving cylinder 35 at the other, that is at their right end. The shaft 62 is journalled at its two ends in bearings 63 and 64 carried by arms 65 and 66 extending downwards, below the adjacent shaft 46, to the support plate 1 on which they are fixed.

As the form of construction corresponds in other respects with that shown in Figs. 3 and 4, the driving means 50, 51, 52, 53 and 54 illustrated in Figs. 3 and 4, act on the bearings 44 and 45 located at the ends of the shaft 46, these driving means being driven by the shaft 39 through the intermediary of the bevel wheel gear 12, 13 and 14 and imparting a reciprocating swinging motion to the shaft 46 and consequently to the separate endless elastic bands 5a, 5b 5c and 5d. Contrary to the construction shown in Figs. 3 and 4, however, the shaft 62 and the longer endless bands 60a, 60b, 60c, 60d and 60e circulating over their rollers and driven by the opposite common driving cylinder 35, do not perform a swinging movement so that these bands can be made of non-elastic material. The longer endless bands bear against the fabric web 2 in the same manner as the short bands in the manner illustrated in Fig. 5 and are preferably closely set with inclined bristles in the same way as that shown in this figure.

The operation of the form of construction illustrated in Fig. 6 corresponds to that of the construction shown in Figs. 3 and 4 so that attention is directed to the foregoing description. The additional separate non-swinging bands 60a, 60b, 60c, 60d and 60e in the construction according to Fig. 6 serve the additional purpose of pressing the fabric web 2 lightly against the support plate 1 and thereby ensuring better running of the fabric web.

It will be evident from the above that the invention is not limited to the specific embodiments shown and disclosed herein by way of example, but that the underlying invention idea and principle are susceptible of numerous variations and modifications coming within the broad scope and spirit of the invention as defined in the appended claims. I wish it to be understood, therefore, that the specification and drawing are to be regarded in an illustrative rather than in a limiting sense.

Although the forms of construction described enable a densification of the fabric merely in the direction of the warp threads, the invention can be applied also for densifying the fabric in the direction of its weft threads.

I claim:

1. An apparatus for the preshrinkage of textile fabrics in continuous webs by mechanically pushing together the fabric, comprising a support plate over which the fabric web is guided, and at least one elastic band arranged above said sup-

port plate, means for imparting a reciprocating swinging motion to said band, said band being at the same time stretched during its swinging movement in the direction opposite to that in which the fabric is pushed together and contracting during its return swinging movement in the direction in which the fabric is pushed together, and means for causing said swinging motion to exert influence on the fabric during the swinging movement of said band in the direction in which the fabric is pushed together and during the stretching of said band.

2. An apparatus for the preshrinkage of textile fabrics in continuous webs by mechanically pushing together the fabric, comprising a support plate over which the fabric web is guided, at least one elastic band arranged above said support plate, means for imparting a reciprocating swinging motion to said band, said band being at the same time stretched during its swinging movement in the direction opposite to that in which the fabric is pushed together and contracting during its return swinging movement in the direction in which the fabric is pushed together, and means for causing said swinging motion to exert influence on the fabric during the swinging movement of said band in the direction opposite to that in which the fabric is pushed together and during the stretching of said band.

3. In an apparatus as specified in claim 1, the means for imparting the swinging movement to the band comprising two cranked shafts one at each end of the support plate and each having a middle part to which the said band is secured and two lateral arms, the lateral arms of the shaft at the feed end of said support plate being longer than the arms of the shaft at the other end of said support plate, and means for rotating said shafts at the same speed.

4. An apparatus for the preshrinkage of textile fabrics in continuous webs by mechanically pushing together the fabric, comprising a support plate over which the fabric web is guided, at least one elastic band arranged above said support plate and contacting the fabric, means for imparting a reciprocating swinging motion to said band, said band being at the same time stretched during its swinging movement in the direction opposite to that in which the fabric is pushed together and contracting during its return swinging movement in the direction in which the fabric is pushed together, and bristles on the side of said band facing the fabric web, said bristles pointing in the direction in which the fabric is pushed together.

5. An apparatus for the preshrinkage of textile fabrics in continuous webs by mechanically pushing together the fabric, comprising a support plate over which the fabric web is guided, at least one elastic band contacting the fabric arranged above said support plate, means for imparting a reciprocating swinging motion to said band, said band being at the same time stretched during its swinging movement in the direction opposite to that in which the fabric is pushed together and contracting during its return swinging movement in the direction in which the fabric is pushed together, said elastic band made entirely of rubber

- and bristles embedded at one end in the surface of said band facing the fabric and pointing downwards in the direction in which the fabric is pushed together.
5. An apparatus for the preshrinkage of textile fabrics in continuous webs by mechanically pushing together the fabric, comprising a support plate over which the fabric web is guided, at least one elastic band contacting the fabric arranged above said support plate, means for imparting a reciprocating swinging motion to said band, said band being at the same time stretched during its swinging movement in the direction opposite to that in which the fabric is pushed together and contracting during its return swinging movement in the direction in which the fabric is pushed together, said band constructed as an endless elastic band, cylinders guiding said band above said support plate, bristles arranged at an incline on the entire outer surface of said band and pointing downwards from the under side of said band in the direction in which the fabric is pushed together, and means for circulating said band on said cylinders.
25. 7. In an apparatus as specified in claim 1, the elastic band consisting of an endless band, two cylinders guiding said endless band over the support plate, and arranged one at each end of the support plate, a stationary shaft carrying the cylinder at the delivery end of said support plate, means for driving said shaft to impart a circulating motion to said band, a shaft carrying the cylinder at the free end of said plate, and means for imparting a reciprocating swinging movement to said last mentioned shaft to periodically stretch and slacken said band while in contact with said fabric and means on said band for pushing together said fabric during the swinging of said band.
40. 8. In an apparatus as specified in claim 1, the elastic band comprising a plurality of separate endless bands, bristles arranged at an incline on the active outer surface of said bands and pointing downwards from the under side of said band in the direction in which the fabric is pushed together, a stationary driven cylinder arranged

above the delivery end of the support plate and supporting one end of said bands in spaced arrangement, rollers arranged above the feed end of the support plate, one roller supporting the other end of each of said bands, a shaft carrying said rollers, means for reciprocating said shaft to periodically stretch and slacken said bands, additional endless bands arranged at one end on said cylinder in the spaces between and laterally of said first mentioned bands and additional rollers supporting the other end of said additional bands and adapted to guide said additional bands with the under side continually in contact with the fabric, and means for driving said cylinder to impart a circulating motion to said elastic bands and said additional bands.

9. An apparatus for the preshrinkage of textile fabrics in continuous webs by mechanically pushing together the fabric, comprising a support plate over which the fabric web is guided, at least one elastic band contacting the fabric arranged above said support plate, means for imparting a reciprocating swinging motion to said band, said band being at the same time stretched during its swinging movement in the direction opposite to that in which the fabric is pushed together and contracting during its return swinging movement in the direction in which the fabric is pushed together, and means for adjusting the amplitude of the reciprocating swinging movement of said band.

10. An apparatus for the preshrinkage of textile fabrics in continuous webs by mechanically pushing together the fabric, comprising a support plate over which the fabric web is guided, at least one elastic band contacting the fabric arranged above said support plate, means for imparting a reciprocating swinging motion to said band, said band being at the same time stretched during its swinging movement in the direction opposite to that in which the fabric is pushed together and contacting during its return swinging movement in the direction in which the fabric is pushed together, and means for varying the number of reciprocating swinging movements of said band.

45. GEORG SCHLENK.
